ATTORNEY.

BY

UNITED STATES PATENT OFFICE.

WALTER A. AUGUSTINE, OF ALAMEDA, CALIFORNIA.

SIGN-PAINTING MACHINE.

No. 852,692.

Specification of Letters Patent.

Patented May 7, 1907.

Application filed March 28, 1906. Serial No. 308,380.

To all whom it may concern:

Be it known that I, WALTER A. AUGUSTINE, a citizen of the United States, residing at Alameda, in the county of Alameda and State of California, have invented certain new and useful Improvements in Sign-Painting Machines, of which the following is a specification.

The object of this invention is to provide a machine for painting signs on boards or other suitable material, so that such signs can be painted rapidly and cheaply, and upon warped or uneven surfaces as well as upon even surfaces; also a machine by which parti-colored color signs can be painted; also by which two or more signs can be painted at each revolution of the machine.

In the accompanying drawing, Figure 1 is a side elevation of the machine, certain parts being broken away; Fig. 2 is a broken bottom plan view thereof; Fig. 3 is a view similar to Fig. 2 of a modification; Fig. 4 is a sectional view of the sheet for producing the impression.

Referring to the drawing, 1 represents a frame having a top 2 and side bars 3. Mounted in bearings on side frame is a driving shaft 4, carrying a gear 5, meshing with a gear 6 upon a shaft 7, mounted in bearings on the side bars 3, said shaft 7 carrying a paint roller 8.

Upon the top of the frame 1 is mounted an auxiliary frame 9 in which are slides 10 forming the bearings of the shaft 11 of a feed roller 12. Said slides and therefore also the feed roller 12, are pressed downward toward the painting roller 8, by means of springs 13 compressed between the top of the frame 9 and collars 14 secured by set screws 15 upon threaded rods 16. By means of handles 17 said rods are screwed through said slides 10, but pass loosely through the frame. By turning the rods in said slides the collars can be moved to or from said slides, thus varying the degree of pressure with which the feed roller bears down upon the painting roller.

The board which is to be painted, shown at 19, rests upon a table 20, the end of which is raised by means of the screw 21. Said table is provided on one side with a wall 22; on the opposite side with a guide 23 adjustably secured in a transverse under cut groove

24 in the table, by means of a screw 25 and thumb nut 26.

The painting roller is formed with a rim 27 of flexible composition which may be similar to that used in printers' rolls. The sheet 28 from which the impression is taken to paint the sign is secured upon the periphery 60 of the printing roller having been prepared as follows. First, the original of the sign is formed upon a sheet of paper. It is then transferred to a sheet of composition molded upon a backing of paper 64, thus producing 65 a negative of the sign. Then part of said sheet of composition is cut away along the outline of the sign. If the sign is to be painted in relief, then the part of the composition outside the outline is removed. If 70 in intaglio, then the part within the outline is removed. This backing of paper having thereon the sheet of composition, with the negative of the sign thus formed thereon, is then secured to the painting roller.

The paint is distributed upon the painting roller by a distributing roller 30, also formed with a rim 31 of yielding composition, and having its shaft 32 in bearings 33 slidably mounted upon the side bars 3. Said distributing roller is pressed against the painting roller by means of coiled springs 34 compressed between the frame 1 and collars 35 secured upon rods 36 screwed through lugs 37 standing from said bearings. Said rods 85 are provided with handles 38 by which they can be turned, so that the position of the collars relatively to the lugs can be adjusted, and thereby the pressure of the compressed springs can be varied. In this way the distributing roller is maintained firmly pressed against the painting roller. It is of great importance that these two rollers should be driven with absolute uniformity, and, for this purpose, from the shafts of said rollers 90 extend arms 39 connected by a link 40 and carrying at their ends bearings for shafts 41, 42 of gears 43, 44, meshing with each other, and also meshing respectively with the gear 6 on the shaft of the painting roller, and with 100 a gear 45 on the shaft of the distributing roller, said gears being of the same size. By this means the painting and distributing rollers are driven in unison, so that there is no slipping of one roller upon the other.

The paint is supplied to the distributing

roller from a paint trough 47, in which is a supply roller 48 the shaft of which has bearings in the lower ends of hangers 49 slideable upon the frame to and from the distributing roller, 5 the trough being also supported by arms 50 from said hangers. Through said hangers are screwed rods 51 having collars 52 secured thereon between which collars and the frame are interposed compressed springs 53, which 10 thus tend to force said supply roller against the distributing roller. The handles 54 facilitate the turning of the rods whereby the compression of said springs may be varied. A second supply roller 55 of like character 15 with the first roller and pressed in like manner against the distributing roller is shown, but this second roller may be omitted. It is used when it is desired to paint in one revolution of the painting roller two signs of different colors, or to paint the sign so that the 20 colors overlap.

In Fig. 2 is shown the arrangement used when it is desired to paint two signs of different colors in one revolution of the painting roller. In such case the distributing rollers carry two pairs of peripheral cams 57 58, the cams of one pair lying outside the cams of the other pair. One of the supply rollers 48 is shorter than the other roller, and is engaged 25 by the inner pair of cams, so as to be raised thereby from the surface of the distributing roller, being permitted to return into contact with the surface of the distributing roller when said cams pass from said supply roller, 30 the shaft of said roller not being then in contact with the other pair of cams. The other supply roller 55 is provided with grooves 59 which enable the surface of said supply roller to avoid the inner pair of cams, while yet said 35 surface is engaged by the outer pair of cams and is raised by them out of contact with the surface of the distributing roller. This permits of two signs being secured upon the painting roller, one of them being painted by 40 the paint received from the supply roller 48, and the other by the paint received by the supply roller 55. It will be observed that 45 the two pairs of cams overlap peripherally at their ends, so that the corresponding portion 50 of the periphery of the distributing roller receives paint of neither color.

In the modification shown in Fig. 3, the cams are not used on the distributing roller, and the two supply rollers contact with the 55 surface of the distributing roller on opposite sides thereof, and to a certain extent overlap, so that, while the top of the sign is painted one color, and the bottom another color, the intermediate part is painted a mixture of 60 the two.

60 is a spreading roller, its shaft being mounted in brackets 61 depending from the side bars 3, and pressed against the distrib-

uting roller in the same manner as the supply rollers.

In order to justify the front end of the sign painted on the board there is provided a spring stop 62 in a recess 63 in the periphery of the printing roll. When the end of the sign is passing beneath the feed roller, said stop can move back as much as is necessary into said recess so as to prevent any undue pressure between said feed roller and the painting roller.

I claim:—

1. In a machine for painting signs, the combination of a painting roll, having a yielding surface, a backing of thin but inextensible material secured to said roll having secured thereon a thicker sheet of composition; a part being cut away to form a negative of the sign to be painted, a distributing roll contacting with the painting roll, means for pressing the distributing roll against the painting roll, and means for causing said rolls to revolve in unison comprising gears on the shafts of the rolls, pinions respectively meshing with said gears and also meshing with each other, links between the ends of the shaft of the pinions, and a link between the shaft of each pinion and that of its corresponding gear, substantially as described.

2. In a machine for painting signs, the combination of a painting roll, having a yielding surface, a backing of thin but inextensible material secured to said roll and having secured thereon a thicker sheet of composition; a part being cut away to form a negative of the sign to be painted, means for distributing paint upon said roll, and means for passing a board into close contact with said roll to take the impression therefrom, substantially as described.

3. In a machine for painting signs, the combination of a painting roll, having a yielding surface, a backing of thin but inextensible material secured to said roll and having secured thereon a thicker sheet of composition; a part being cut away to form a negative of the sign to be painted, means for distributing paint upon said roll, comprising a distributing roll and positive means for causing said painting and distributing rolls to revolve in unison, and means for passing a board into close contact with said roll to take the impression therefrom, substantially as described.

4. In a machine for painting signs, the combination of a painting roll, having a yielding surface, a sheet of yielding material secured to said roll and having a part cut away to form a negative of the sign to be painted, means for distributing paint upon said roll, comprising a distributing roll, means for pressing said distributing roll against the painting roll comprising movable

bearings for the shaft of the distributing roll, springs pressing against said bearings, and means for adjusting said springs, comprising collars against which the springs abut, 5 threaded rods through collars for said rods and means for turning said rods in said bearings, means for causing said painting and distributing rolls to revolve in unison, and means for passing a board into close contact

with said roll to take the impression therefrom, substantially as described.

In witness whereof I have hereunto set my hand in the presence of two subscribing witnesses.

WALTER A. AUGUSTINE.
